UNITED STATES PATENT OFFICE.

FREDERICK NEVINS, OF BROOKLYN, NEW YORK, ASSIGNOR TO MOREWOOD STANDARD SAFETY DEVICES CO., OF NEW YORK, N. Y.

ANCHOR-BOLT.

969,111.

Specification of Letters Patent. Patented Aug. 30, 1910.

Application filed April 6, 1910. Serial No. 553,697.

To all whom it may concern:

Be it known that I, FREDERICK NEVINS, a citizen of the United States, and a resident of the borough of Brooklyn, county of Kings, and State of New York, have invented certain new and useful Improvements in Anchor-Bolts, set forth in the following specification.

This invention relates to anchor bolts particularly adapted for use in connection with safety window cleaning apparatus.

The object of the invention is to provide for the anchorage of bolts of the above type between courses of brick, terra cotta blocks or blocks of any well known material and size and in a manner such that the anchoring means shall be universal and equally well adapted for use with bricks or blocks of varying sizes.

A further object of the invention is to provide for the utilization of the window frame in effecting the anchorage of the bolt.

Further objects of the invention are to provide for the general improvement in and the strengthening of an anchor bolt of the type described.

The above will be pointed out more in detail in the accompanying claims, which should be read in connection with the accompanying drawings, which form part of this application and in which,

Figure 1 is a plan view, with parts broken away and parts in section, showing the relative location and arrangement of an anchor bolt embodying the invention; Fig. 2 is a perspective view of a preferable embodiment of the anchor bolt; Fig. 3 is a vertical section taken immediately in the rear of the guard-flange and showing the relation of the anchorage to the overlying and underlying building blocks or bricks; and Fig. 4 shows a modification in the contour of the anchor bolt.

This anchor bolt comprises projecting parts of any usual construction, namely, the bolt head 1, neck 2, and guard-flange 3.

It has heretofore been customary to connect the guard flange with a rearwardly extending web of a width not exceeding the diameter of the flange 3 and to provide for the anchorage of this web by a plurality of extensions extending at right angles to one another and providing offset lips to embrace a brick about at least two edges at right angles one to the other. This construction

necessitated the provision of an anchor bolt of a size to conform exactly to the size of the bricks or building blocks to be employed and was limited in strength to the strength of the narrow web connecting with the flange 3.

To overcome the limitation, the applicant employs a flat web portion 4, cast integrally with the flange 3 and extending laterally beyond the flange 3 into the projection 5 and with its outer edge 6 substantially flush with the inner face 7 of the flange 3. The web also continues rearwardly into a connecting portion 8 which is provided with a lateral extension 9 at its end. The lateral extensions 5 and 9 terminate at the same distance from and at the same side of the axis or center line of the throat 2 and are provided with offset anchoring lips 10, 11 and 12, 13 respectively.

To strengthen the attachment of the web 4 to the bolt head buttresses 14 and 15 at right angles to the web 4 and at opposite sides thereof are cast integrally with the web 4 and flange 3.

From the drawings it is apparent that the web construction comprising the lateral extensions 5 and 9 and the connecting portion 8 form a substantially flattened U shaped web to one corner of which the bolt head structure 1 etc. is fixed.

The above anchor bolt construction is designed to be built into a building wall at the proper elevation above the sill of a window opening. The entire web structure 5, 8, 9 is placed flat against top surface of a brick or building block 16 with the downwardly projecting lips 10 and 11 occupying the crack between the block 16 and the vertical outer wall of the sash weight box 17 of the window frame. The straight edge 6 of the leg 5 is arranged to lie flush with the window opening surface 18 of the block 16 which necessitates merely a small nick 19 being formed in the edge thereof to accommodate the buttress 15. The brick or block 20 of the next tier is placed over the web structure and mortar covered top surface of block 16 and is likewise provided with a nick 21 to accommodate the buttress 14, 105 while its inner face engages the upward extending lips 11 and 13.

In completing the window construction the side frame or window trim 22 is secured to the wall in an ordinary manner as by

screws 23 so as to overlap the leg 5 and clamp over its edge 6. This trim 22 serves to lock the anchor bolt construction in the wall in addition to the locking of the mortar filling between blocks.

By reason of the fact that the legs 5 and 9 extend only to one side of the structure and lips such as 10, 11, 12 and 13 are provided only in a single plane this anchor construction adapts itself to any size of building block without requiring the formation of recesses to accommodate retaining lips. It may, therefore, be termed an universal anchor bolt.

15 In the figures the reveal at the window opening is only that provided by one tier of bricks although it is to be understood that the number of tiers is immaterial so long as the locking lips 10, 11, 12 and 13 engage over the inner edges of the inner tier as shown.

20 Although this anchor bolt may be formed of any suitable material, it is preferred that the same be cast from bronze because of its combined strength and weather resisting qualities.

25 It is, of course, to be understood that the actual contour of the web portions of the anchor bolt may vary and still embody the features of this invention. For instance 30 Fig. 4 shows a web construction of modified contour which also is an embodiment of this invention as covered by the accompanying claims.

35 What is claimed and what is desired to be secured by United States Letters Patent is:—

1. An universal anchor bolt comprising a projecting bolt head and a rearwardly extending flat web portion and a plurality of flat legs lying in the plane of said web portion and extending laterally from the same side thereof and each provided with an offset anchor lip, said lips occupying the same

plane at right angles to the plane of said web portion and substantially parallel to the axis of said projecting bolt head.

45

2. An universal anchor bolt comprising the bolt head 1, the throat 2, the guard flange 3, the web member cast integral with the flange 3 and having the laterally extending leg 5 with its edge flush with the rear face of the flange 3 and provided with an offset anchor lip at its end and having a rearwardly and laterally extending web portion providing a second offset anchor lip in the same plane as that at the end of leg 5.

50

3. An anchor bolt comprising a projecting bolt head; a guard flange adapted to lie flush against the building wall of a window opening; a neck connecting said guard flange and said bolt head; and a rearwardly and laterally extending flat web portion fixed to said guard flange and having an exposed edge extending laterally at right angles to the axis of said bolt head and in the same plane as the rear face of said guard flange so as to lie flush with the surface of a building wall at a window opening.

55

4. In combination in building construction, an anchor bolt having an outer engageable part projecting into the window opening and a flat web portion extending rearwardly with its edge substantially flush with the window opening surface of the reveal, lying between two courses of building blocks, and having offset anchoring means solely at the inner edge of the inner tier of said reveal.

60

In witness whereof, I have signed my name to this specification, in the presence of two subscribing witnesses.

FREDERICK NEVINS.
